The article is a gland for pipe joints used for joining cast iron pipes for water supply; the right views of designs 1 to 6 are omitted because they are mirror images of the left views (Figs. 1.5, 2.5, 3.5, 4.5, 5.5, 6.5) respectively; the bottom views of designs 1, 2, 4, and 5 are omitted because they are mirror images of the top views (Figs. 1.6, 2.6, 4.6, 5.6) respectively; Figs. 1.7, 2.7, 3.8, 4.7, 5.7, 6.8 are cross-sectional views taken along the A-A' line shown in the front views (Figs. 1.3, 2.3, 3.3, 4.3, 5.3, 6.3) respectively; Figs. 1.8, 2.8, 3.9, 4.8, 5.8, 6.9 are enlarged views of the B-B'

portion shown in the cross-sectional views (Figs. 1.7, 2.7, 3.8, 4.7, 5.7, 6.8).
